UNITED STATES PATENT OFFICE.

GEORGE A. SOMMERS, OF MARSHFIELD, WISCONSIN.

TOWEL HOLDER.

Application filed February 7, 1920. Serial No. 356,853.

To all whom it may concern:

Be it known that I, GEORGE A. SOMMERS, a citizen of the United States, residing at Marshfield, in the county of Wood and State 5 of Wisconsin, have invented certain new and useful Improvements in Towel Holders; and I do hereby declare the following to be a full, clear, and exact description of the invention, such as will enable others skilled in 10 the art to which it appertains to make and use the same.

This invention relates to certain new and useful improvements in towel holders and has for its primary object the provision of a 15 device which will permit towels to be freely clamped therein and supported by the device in such a manner that any pull upon the towel will serve to tighten the same in the holder.

Another object of the invention resides in 20 the provision of a towel holder of the above stated character which will efficiently grip the towel but will permit ready removal thereof, when desired.

The invention has for a further object, the 25 provision of a towel holder of the above stated character which will be of simple and inexpensive construction, highly durable and efficient, which may be manufactured at 30 a small cost and in which the diverging clamping arms will be drawn toward one another to securely grip the towel whenever a pull is exerted upon the same.

With the above and other objects in view 35 as will become apparent as the description proceeds, the invention consists in certain novel features of construction, combination and arrangement of cooperating parts, as will be hereinafter more fully described and 40 claimed and shown in the accompanying drawings, in which:—

Figure 1 is a side elevation of a towel holder constructed in accordance with my 45 invention, and illustrating the same with a towel corner clamped therein.

Figure 2 is a similar view with the towel removed.

Figure 3 is a view of the lower portion of 50 the towel holder with the towel mounted therein and showing the side opposite to that disclosed in Figures 1 and 2, in order that the manner of engaging the towel corner with the holder for clamping engagement therein may be more readily understood, a portion of the towel being 55 broken away.

Referring more in detail to the drawings in which similar reference characters designate corresponding parts throughout the several views, 1 indicates the main leg of the shank from which the hanger is formed and 60 2 the ring formed by turning the upper end of the main leg 1 and within which ring 2, is engaged the ring or head of an eye bolt 3 for attaching the shank or entire 65 holder to a stationary support. The shank is turned upon itself at the lower end of the main leg 1 and bent upwardly to form the second or auxiliary leg 4 which diverges slightly from the main leg 1. The second 70 or auxiliary leg 4 is somewhat shorter than the main leg 1 and has its end turned to form an eye 5 which presents a rounded end to prevent the towel 6 or the like positioned upon the hanger from being caught on the 75 free end of the second or auxiliary leg 4 when being engaged upon the hanger or removed, as will be readily understood.

In applying a towel or the like to the hanger or holder, one corner of the towel 80 or other article to be suspended from the hanger is engaged between the legs 1 and 4 in the bottom of the space between the legs 1 and 4 and at which point the legs 85 are slightly separated, as will be readily understood by referring to Figure 2 of the drawings. The towel is then extended completely around both of the legs 1 and 4 in either direction and again engaged through 90 the opening between said legs 1 and 4 and brought downwardly over the projecting corner. This corner has been designated by the numeral 7, in the drawings, while the portion wrapped around the two legs 1 and 4 is designated by the numeral 8 and the portion of the towel brought a second time 95 through the space between the legs 1 and 4 and drawn downwardly is designated by the numeral 9. It will be readily apparent that when the towel is engaged over the 100 holder in this manner, the corner is securely clamped therein and any pull downwardly upon the towel will only tend to draw the legs 1 and 4 closer together and thereby compel them to clamp securely the portions 105 of the towel corner engaged between the legs 1 and 4. Therefore, a secure clamping action of the legs 1 and 4 is caused by the manner in which the towel is engaged therewith, it being understood that the holder is 110 formed of a suitable resilient material such as a heavy wire strand.

By constructing the hanger in the manner shown and described, the towel or other article to be suspended therefrom may be readily engaged in clamping position there-
5 with or removed, as desired.

While the preferred embodiment of the invention has been shown and described, it will be understood that minor changes in the details of construction, combination and
10 arrangement of parts may be resorted to within the scope of what is claimed without departing from the spirit of the invention.

What is claimed is:—

15 A holder consisting of a length of wire folded upon itself to provide clamping legs substantially throughout and of unequal length with the shorter leg at its free end diverging from the longer leg, the longer leg terminating in a ring by means of which

the holder may be pivotally suspended from 20 a support, the short leg terminating below said ring whereby a space is provided between the same and the support by the greater length of the other leg so that said suspending means and ring will not obstruct 25 the attachment of an article to the holder, the connected end of the legs being lowermost an outwardly extending eye at the free end of the shorter leg, and said legs being spaced apart to enable a suspended article 30 to be wrapped about the holder a plurality of times.

In testimony whereof I affix my signature in presence of two witnesses.

GEORGE A. SOMMERS.
